MECHANICAL CLUTCH

Filed Oct. 16, 1930

FIG. 1

FIG. 2

FIG. 3

Inventor
Paul Bischof

By his Attorney J. Ledermann

UNITED STATES PATENT OFFICE

PAUL BISCHOF, OF NEW YORK, N. Y.

MECHANICAL CLUTCH

Application filed October 16, 1930. Serial No. 489,020.

The main object of this invention is to provide a transmission clutch for auto-motive vehicles which is capable of slow and gradual engagement with the drive shaft of the transmission.

Another object is to provide a transmission clutch which is inexpensive in cost of manufacture of a minimum number of parts and fool-proof and sure in operation.

The above and other objects will become apparent in the description below in which characters of reference refer to like-named parts in the drawing.

Referring briefly to the drawing, Figure 1 is a longitudinal sectional elevational view through the clutch in disengaged position.

Figure 2 is a fragmentary front elevational view of the same.

Figure 3 is a front elevational view of the grip shoe.

Referring in detail to the drawing, the numeral 10 indicates the motor drive shaft which has secured to its end a dished-out fly-wheel 11. The fly-wheel is secured to the shaft 10 by bolts 12. A driven shaft 13 is mounted co-axial with the drive shaft and has a disc 14 slidably mounted on the driven shaft and is rotatable with the latter. The disc is provided with flat parallel faces 15 and 16, the former of which is adapted to engage the face surface 17 of the fly-wheel 11. The face 16 of the disk 14 is normally in contact with the flat friction grip surface 18 of a ring 19. Said ring is normally urged into contact with the disk by springs 20 arranged around the ring 19 and which have one end housed in provided cups 21 of a base plate 22 which is rigidly secured to the fly-wheel 11 and provided with oppositely-disposed fixed collars 23 and 24.

The ring 19 is provided with an annular channel 25 in which is received a grip shoe 26 which has its underside provided with serrations 27 engageable with complementary serrations 28 formed on the surface 16 of the ring 14. The circular shoe 26 is provided with a plurality of studs 29 which pass through suitable openings in the ring 19 and through openings in the base plate and normally project somewhat above the latter.

The projecting ends of the studs 29 are pivotally secured to levers 30 which latter rest on lugs 31 of the base plate intermediate their length. The free ends of the levers are supported on coil springs 32 and ride upon one side of a shoulder plate 33 which is mounted slidably on the driven shaft 13.

A foot pedal 34 is pivotally mounted above the floor board (not shown) of the vehicle and is connected to a fulcrummed lever 35 through the medium of a connecting bar 36.

In use, the device is adapted to uncouple the driven shaft from the drive shaft when required so that the vehicle of which the device forms a part may be halted. By urging the foot pedal 34 forwardly, the shoulder plate 35 is slid along the driven shaft toward the fly-wheel 11 of the device. The levers 30 which have their ends connected to the studs 29 will lift the circular shoe 26 away from the ring 14 thereby releasing the serrations on both of these members from mutual engagement. The ring 19 is then lifted from the face of the disk 14 thereby completely uncoupling the clutch. By releasing the foot pedal the stated members are urged into engaged position by the springs 20 and 32.

It is to be noted that certain changes in form and construction may be made without departing from the spirit and scope of the invention.

I claim:

In a device of the class described, a drive shaft having a fly wheel thereon, a driven shaft having a disk thereon normally in frictional contact with the fly wheel, said disk having raised pointed serrations thereon, a floating ring housed in said fly wheel, said ring having an annular channel therein, an annular serrated shoe movable in said channel normally engaging said disk, and means on said shoe for retracting said shoe to release the clutch.

In testimony whereof I affix my signature.

PAUL BISCHOF.
